PORTABLE AIR POWERED VACUUM CLEANER

Frank Polizzi, 305 La Jolla Drive,
Newport Beach, Calif. 92037

Filed Apr. 11, 1966, Ser. No. 1,825

Term of patent 14 years

(Cl. D9—2)

FIG. 1 is a top plan view of an air powered vacuum cleaner showing my new design;

FIG. 2 is a side elevation view thereof, both sides of the portable air powered vacuum cleaner being identical in appearance;

FIG. 3 is a front end elevation view thereof; and,

FIG. 4 is a bottom plan view thereof.

I claim:

The ornamental design for a portable air powered vacuum cleaner, substantially as shown and described.
